UNITED STATES PATENT OFFICE

2,590,705

FILM RACK

Cornelius S. Hurlbut, Jr., Belmont, Mass., assignor to Cambridge Thermionic Corporation, Cambridge, Mass., a corporation of Massachusetts

Application January 25, 1949, Serial No. 72,705

2 Claims. (Cl. 95—100)

1

This invention relates to apparatus for handling photographic film and more particularly to a rack for supporting strips of film during and after the various procedures of a photographic process.

Objects of this invention are to provide a rack which will receive one or more strips of photographic film, which will accommodate strips of varying lengths and width, which prevents the film strips from curling, which prevents adjacent film strips from contacting one another, which is simple to use, which is economical in construction, and which is especially compact, occupying a minimum of space while permitting inspection of the films.

In a broad aspect the invention contemplates a supporting frame having one or more pairs of parallel guides and fastening means to secure one end of each strip of film to the frame. The opposite end of each film strip is gripped by a respective clamp of a stretching means which is slidably attached to a correlated pair of guides. Means are provided for moving the stretching means along the correlated guides whereby the film is extended so that the film is prevented from curling while drying.

In different aspects the means for moving the stretching means along the guides may be a spring disposed between the frame and the stretching means, a weight suspended from the stretching means or the inherent mass of the stretching means itself.

In a specific aspect the invention contemplates a rack comprising a supporting frame having two upright members, the respective upper ends of which are joined by a crosspiece. A similar crosspiece extends between the lower ends of the respective members. A plurality of parallel guides are interposed between the crosspieces. The upper crosspiece is provided with a plurality of stationary clamps for securing the respective film strips. The other end of each film strip is gripped to by a movable clip which is slidably attached to two adjacent guides. The clip is moved along the guides by its own mass or by an external weight or spring.

A particularly important feature of the invention is the arrangement of the alternate guides in parallel planes so that the clips attached to adjacent guides are arranged at an angle with respect to the plane of the frame. This arrangement allows the successive film strips to be staggered thus increasing the number of strips accommodated by a given size frame, while not impeding inspection of each individual strip.

2

These and other objects, aspects and features will be apparent from the following description of an illustrative specific embodiment of the invention referring to drawings in which

5 Fig. 1 is a side elevation view of one embodiment of the invention;

Fig. 2 is a cross-sectional view on line 2—2 of Fig. 1;

Fig. 3 is a side elevation view of a second embodiment of the invention;

Fig. 4 is a cross-sectional view on line 4—4 of Fig. 3;

Fig. 5 is a cross-sectional view on line 5—5 of Fig. 3; and

15 Fig. 6 is an enlarged isometric view of the movable clip.

The photographic film drying rack 10 (Fig. 1) chosen for the purpose of illustration, comprises a supporting frame 11 having two upright members 12. The respective upper ends of the upright members 12 are welded or otherwise joined to a crosspiece 13 preferably having a channel shaped cross-section. A similar crosspiece 14 connects the lower ends of the upright members 12.

20 A plurality of wires or rods such as the guides 16 are interposed between the crosspieces 13 and 14, alternate guides being located in parallel vertical planes. One end, preferably the bottom of each guide 16, is riveted or peened over, the other end of the rod being threaded to engage a nut 15 so that the tension of the guide can be regulated by adjustment of the nut. Each strip of film F to be treated is supported at one end by fastening 30 means such as the stationary clips 17 (Fig. 5). The clips 17 are secured to the web of the top crosspiece 13 by means of the rivets 18 which project through apertures located in the web midway between the guides 16 of each staggered 35 pair.

40 The clip 17 comprises two jaws 21 and 22 having mating serrated ends for gripping the film strip F therebetween. The opposite end 20 of the jaw 21 is bent perpendicularly to the remainder of the jaw to provide a lip having an aperture through which projects the rivet 18 securing the clip 17 as mentioned above. Interposed 45 intermediate the ends of the jaw 21 are two tabs 23 bent normally to the opposite sides of the jaw 21 and each having an aperture therein through which projects a pin 24. The pin 24 also engages apertures in similar tabs 26 of the jaw 22. The opposite end 27 of the jaw 22 is also extended 50 to provide a lever for opening the jaws 21 and 22 against the closing force of a spring 28 which is

55

disposed circumjacent the pin 24 with its ends bearing against the extended jaw ends 20 and 21, respectively.

The opposite end of each film strip F is gripped by a clamp 31 of stretching means such as the clip 19 having a runner 32, the hooked ends of which are slidably attached to two adjacent guides 16. The clamp 31 (Fig. 6) comprises two jaws 33 and 34 each having a serrated end which mates with the serrated end of the other jaw. Two tabs 36 having respective apertures therein for engaging a pin 37 are bent normally to the opposite sides of the jaw 34. The jaw 33 has two similarly disposed apertured tabs 38. The serrated edges of the jaws 33 and 34 are forced into engagement by a spring 39 which is positioned circumjacent the pin 37 with the ends thereof bearing against the inner surfaces of the ends 41 and 42 of the jaws 33 and 34, respectively. The runner 32 is riveted or otherwise fastened to the outer surface of the jaw 33.

In order to attach a film strip F to the rack, one end thereof is secured in one of the clamps 17, the jaws 21 and 22 thereof being separated so that the film strip can be inserted by depressing the ends 20 and 21 with the forefinger and thumb. The jaws 33 and 34 of the correlated clamp 31 are opened by depressing the ends 41 and 42 in a similar manner and the runner 32 moved along the guides 16 until the jaws engage the opposite end of the film strip F. The clip 19 is then released and the weight thereof stretches the film strip F so that it does not curl. The remaining film strips F are attached in a similar manner. The guides 16 prevent adjacent film strips F from coming into contact with one another during treatment and when the drying air is circulated either mechanically or naturally to decrease the drying time. If the weight of the clip 19 is not sufficient to prevent the film strips from curling, the effective mass thereof can be increased by hanging a weight 44 in an aperture 43 provided in the end 42 of the jaw 34 for such purpose. The staggered or louvre-like arrangement of the films permits easy inspection while considerably reducing the area required by a rack designed for holding a given amount of film.

Another embodiment of the rack 10^a is shown in Fig. 3 wherein the force for extending the film strip F is supplied by means of a spring 45 interposed between the clip aperture 43 and the bottom crosspiece 14. The guides 16 have also been rearranged so that they all lie in one vertical plane as is shown in Fig. 4. The remaining elements bear similar indicia to the corresponding elements of the rack 10 which has been described in detail heretofore.

It should be understood that the present disclosure is for the purpose of illustration only and that this invention includes all modifications and equivalents which fall within the scope of the appended claims.

5 I claim:

1. A rack for supporting a plurality of strips of photographic film comprising a supporting frame, a plurality of parallel guides the ends of which 10 are attached respectively to opposed sides of the frame, alternate guides being located in two parallel planes, fastening means for securing the respective ends of the film strips to said frame, a plurality of stretching means each attached to a guide in one vertical plane and an adjacent guide 15 in the parallel plane so as to be freely slidable thereupon and having a clamp to grip the opposite ends of the respective said film strips, and means for moving the stretching means along said 20 guides whereby the film strips are prevented from curling.

2. A rack for supporting a plurality of photographic film strips comprising a supporting frame having two upright members and two crosspieces, 25 one piece extending between the upper ends of the respective members and the other piece between the lower ends of the members, a plurality of parallel guides the ends of which are attached respectively to said crosspieces, alternate guides 30 being located in two parallel planes, a plurality of stationary clamps for securing the respective film strips to the crosspiece extending between the upper ends of the members, a plurality of movable clamps each attached to a respective guide in one 35 vertical plane and an adjacent correlated guide in the parallel plane so as to be freely slidable thereupon and arranged to grip the opposite ends of said respective film strips, and a plurality of 40 weights attached to the respective movable clamps for sliding the movable clamps along said guides whereby the film is prevented from curling.
